UNITED STATES PATENT OFFICE.

ROBERT H. ROARK, OF WACO, TEXAS.

MACHINE FOR SCORING ICE.

Application filed November 29, 1924. Serial No. 752,905.

To all whom it may concern:

Be it known that I, ROBERT H. ROARK, a citizen of the United States, residing at Waco, in the county of McLennan and State of Texas, have invented a new and useful Machine for Scoring Ice, of which the following is a specification.

This invention relates to machines for scoring blocks of ice, so as to insure the accurate cutting thereof into predetermined sizes for the retail trade.

The general object of the invention is to provide, in a machine of this type, improved means for supporting and operating the saws in conjunction with the block of ice, whereby the same is rendered simpler and more practical, and may be installed with less trouble. In machines of this type, as heretofore constructed, the vertical kerfs are formed either by moving the ice vertically while the saws rotate about a fixed axis, or by mounting the saws on a carriage which reciprocates vertically while the block of ice remains stationary. In the latter case, if the block rests on the floor, it is necessary to cut recesses or slots in the floor to permit the saws to descend far enough to cut the kerfs to the lower edge of the block. This is objectionable for various reasons. According to the present invention, however, the block of ice is raised, while the saws, at the same time, descend, and the ice cage and saw frame are so connected and arranged that the weight of one serves as a counter-balance to the weight of the other, thus conserving power, as well as obviating the very objectionable feature of cutting the floor.

The invention will be more particularly described with reference to the accompanying drawings, which illustrate the same in its preferred form.

In the drawings:

Figure 1 is a side elevation of the machine.

Figure 2 is a plan view thereof.

Figure 3 is a horizontal section taken on the line 3—3 of Figure 1.

Figure 4 is an end elevation.

Figure 5 is a transverse section taken on the line 5—5 of Figure 1.

Referring to the detailed construction of the machine, the same comprises a stationary frame, secured to a floor or platform, and including upright posts 1, connected by horizontal beams 2, and within this main frame is a supplemental frame or saw car-

riage, having longitudinal beams 3 connected by transverse beams 4, and vertical hanger bars 5, on the outer faces of which are mounted rollers 6, which are adapted to travel in vertical guideways 7 formed on the vertical posts 1. The hanger bars 5 have bearings 8 at their lower ends in which arbors 9 are journaled, the latter having series of saws 10 secured thereto for cutting the vertical kerfs on opposite faces of the block of ice.

The main power shaft 11 is suitably mounted in bearings 12 secured to the upper part of the main frame, and is driven from any suitable source of power through the medium of a motor 13, or its equivalent. The power shaft 11 is connected by a belt 14, or other similar means to a countershaft 15 suitably mounted on the main frame, and having beveled gears 16 operatively connected with beveled gears 17 at the upper ends of vertical shafts 18 located near one end of the machine. The shafts 18 have a driving connection with the arbors 9, which will permit the saw frame to be raised and lowered while the saws are being operated. This connection preferably consists of intermeshing worm gears 19 and 20 secured respectively to the shafts 18, and the extended end portions of the arbors 9. Horizontal saws 21 may also be secured to the shafts 18 at a proper height to cut the longitudinal kerfs in the block of ice as the latter leaves the machine.

The shaft 15 also has a spur gear 22 secured thereto, which meshes with a spur gear 23 secured to a transverse shaft 24, and the latter has a sprocket wheel 25 secured to its rear end and connected by a sprocket chain 26 to a sprocket wheel 27 secured to a transverse shaft 28 journaled in the upper part of the main frame, substantially midway between its ends. A beveled gear 29 is secured to the shaft 28 near one end thereof, and meshes with a beveled gear 30 loosely mounted on a short longitudinal shaft 31, which is journaled near one side of the frame. A clutch member 32 is keyed to the shaft 31 and normally urged by an expansile coiled spring 33 into engagement with the beveled gear 30, which is adapted to be constantly driven. The shaft 31 has beveled gears 34 secured to its ends, and meshing with beveled gears 35 secured on shafts 36, which are journaled transversely of the main frame. Each of the shafts

36 has a spur gear 37 secured thereto midway of its ends, which meshes with a vertically disposed rack 38 secured to a vertical bar 39, which forms a part of the vertically reciprocating frame or saw carriage. Cords or cables 40 are secured at one end to the horizontal beams 3 of the reciprocating carriage and pass over sheaves 41 loosely mounted on the shafts 36, and are connected at their other ends to eyes 42 secured to the upper side of a cage 43, which is adapted to receive a block of ice 44. Suitable guides 45 may be provided for guiding the cage 43 vertically, and when the clutch 32 is engaged, the shafts 36 will be driven to lower the racks 38 and the saws 10, while at the same time, through the medium of the cables 40, the cage 43 and block of ice 44 are raised to cut the vertical kerfs 46.

20 The position of the clutch 32 is controlled by means of a forked lever 47, which is pivotally connected at 48 to an arm 49, the other end of which is pivoted at 50 to the main frame. A roller 51 is mounted on the pivot 48, and as the saw carriage descends and the cage 43 rises, the latter engages the roller 51. The two arms 47 and 49 form, in effect, a toggle, which is spread when the cage 43 engages the roller 51, and this disengages the clutch and allows the cage 43 and block of ice 44 to drop. It is to be understood that the weight of the block of ice is sufficient to more than balance the weight of the saw carriage, and, if desired, a suitable check may be provided to prevent a too rapid descent of the ice cage. A rod 52 is pivoted at one end to the lever 47, and extends forwardly through a slot 53 in the saw frame, and is provided with a detent 54, which locks the clutch 32 out of engagement until manually released.

45 After the kerfs 46 have been cut, and the cage 43, containing the block of ice, again rests upon the floor, a pusher 55 carried by a sprocket chain 56 is adapted to engage the end of the block and discharge it from the machine. The chain 56 is mounted on sprocket wheels 57 and 58 secured to vertical shafts 59 and 60 respectively, the shaft 50 60 being extended upwardly and provided at its upper end with a beveled gear 61, which is driven by a beveled gear 62 secured to the transverse shaft 24. The ratio of the gearing is such that there is plenty of time for the reciprocation of the carriage 43 before the pusher 55 reaches a position to engage the ice.

60 In the operation of the machine, the block of ice is introduced into the cage 43 from the right hand end of the machine, as viewed in Figure 1. When the block of ice has been placed in proper position, the latch rod 52 is manually released to throw the clutch 32 into engagement, whereby the shafts 36 are driven to positively lower the saw carriage,

at the same time raising the cage 43 carrying the block of ice. If the block of ice were to remain upon the floor while the saws 10 were lowered, it would, of course, be necessary to cut slots in the floor to permit the kerf 46 to be cut entirely across the face of the block. This would be a very objectionable feature, especially when the floor is made of concrete. By the present arrangement, however, the block of ice 44 travels the same distance as the saw carriage, and as the cage 43 comes in contact with the roller 51, the clutch is automatically disconnected and the block of ice descends by gravity to the floor. By observing the position of the pusher 55, the operator may place the block of ice in the cage and release the latch rod in time for the upward and downward movement of the cage to be completed before the block of ice is engaged by the pusher 55 and discharged from the machine. As the block of ice is discharged, it is scored longitudinally by the saw 21. The weight of the cage 43 is sufficient to maintain the saw carriage raised until the latch rod 52 is manually released to throw the clutch 32 again into engagement.

55 While I have shown and described the various parts of the machine in considerable detail, it is to be understood that this is only for the purpose of illustrating one form in which the invention may be embodied. It is quite obvious that many modifications may be made in the arrangement of the gearing and in other parts of the machine without departing materially from the salient features of the invention. It is my purpose, therefore, to include all such modifications within the scope of the appended claims.

105 What is claimed is:

1. In a machine for scoring ice, the combination of a saw carriage with saws mounted therein, a cage adapted to receive a block of ice, and means for moving the carriage and cage simultaneously in opposite directions to cause the saws to score a block of ice carried in said cage.

110 2. In a machine for scoring ice, the combination of a saw carriage having vertically disposed saws mounted therein, a cage adapted to receive a block of ice, and means for simultaneously moving said carriage and cage vertically in opposite directions to bring the saws into operative relation to a block of ice carried by said cage.

115 3. In a machine for scoring ice, the combination of a saw carriage having vertically disposed saws mounted therein, a cage adapted to receive a block of ice, and means for positively moving the carriage downwardly in a vertical direction and at the same time lifting the cage with a block of ice therein.

120 4. In a machine for scoring ice, the combination of a saw carriage having longi-

- itudinally disposed arbors journaled therein, opposed circular saws secured to said arbors, a cage adapted to receive a block of ice, means for simultaneously moving said carriage and cage vertically in opposite directions, and means for rotating the saws continuously during their vertical movement.
5. In a machine for scoring ice, the combination of a saw carriage having vertically disposed saws mounted therein, a cage adapted to receive a block of ice, gearing operable to positively move the carriage downwardly in a vertical direction, at the same time lifting the cage with a block of ice therein, a clutch controlling the operation of said gearing, and means for automatically disconnecting the clutch when the carriage completes its downward movement.
10. 6. In a machine for scoring ice, the combination of a saw carriage guided for vertical movement, a cage adapted to receive a block of ice and also guided for vertical movement, gearing for positively moving the carriage downwardly and at the same time lifting the cage with a block of ice therein, a clutch controlling the operation of said gearing, spring means normally holding the clutch in engagement, means engageable by the ascending cage for automatically disconnecting the clutch when the cage completes its upward movement, and a latch operable to lock the clutch out of engagement until said latch is manually released.
15. 7. In a machine for scoring ice, the combination of a stationary main frame, a saw carriage guided for vertical movement therein, a cage guided for vertical movement and adapted to receive a block of ice, gearing for positively moving the carriage downwardly and at the same time lifting the cage, a clutch controlling the operation of said gearing, and a toggle having one arm pivoted to the frame of the saw carriage and the other arm engaging said clutch, the cage as it ascends being engageable with the toggle to spread the same and automatically disengage said clutch.
20. 8. In a machine for scoring ice, the combination of a stationary main frame, a saw carriage guided for vertical movement therein, a cage adapted to receive a block of ice, said cage being also guided for vertical movement, sheaves rotatably supported by the main frame, cables trained over the sheaves and each secured at one end to the frame of the saw carriage and at the other end to the cage, gearing for positively moving the carriage downwardly and at the same time lifting the cage, and means for automatically disconnecting said gearing, the weight of said cage and the block of ice being sufficient to overbalance the weight of the saw carriage and return the latter to its uppermost position.
25. 9. In a machine for scoring ice, the combination of a saw carriage having vertically disposed saws mounted therein, a cage adapted to receive a block of ice, means for positively moving the carriage downwardly and at the same time lifting the cage with a block of ice therein, means for returning the saw carriage while the ice cage moves downwardly, a pusher engageable with the block of ice to discharge it from the cage after the latter descends, and means for scoring the block longitudinally during its discharge.
30. 10. In a machine for scoring ice, the combination of a stationary main frame, a saw carriage and an ice cage mounted for vertical movement therein, sheaves rotatably supported by the main frame and having cables trained over them with their ends connected to the saw carriage and ice cage respectively, whereby the carriage and cage move in opposite directions, gearing for positively moving the carriage downwardly to lift the cage with a block of ice therein, a clutch controlling the operation of said gearing, means for automatically disconnecting the clutch at the completion of the downward movement of said carriage thus permitting the latter to be raised by the weight of the ice, a pusher engageable with the block of ice to discharge it from the cage after the latter descends, and means for scoring the block longitudinally during its discharge.
35. 11. In a machine for scoring ice, the combination with a series of saws, means for supporting the same for rectilinear vertical movement, means for supporting a block of ice for vertical movement, and unitary means for moving the ice supporting means and the saws-supporting means simultaneously to carry the ice toward and from the saws.
40. 12. In a machine for scoring ice, the combination with a series of saws, means for supporting the saws for bodily rectilinear movement, means for supporting a block of ice, and unitary means for simultaneously moving the ice-supporting means and the supporting means for the saws in predetermined relation to each other to carry the ice toward and from the saws.
45. 13. In a machine for scoring ice, the combination with a series of saws, means for supporting the saws for bodily movement, means for supporting a block of ice, and means for simultaneously moving the ice-supporting means and the supporting means for the saws to carry the ice toward and from the saws, said saws-supporting means and the ice supporting means being connected together so that the weight of one serves as a counterbalance to the weight of the other.
50. 14. In a machine for scoring ice, the combination with a series of saws, means for

supporting the same for bodily rectilinear movement, means for supporting a block of ice, unitary means for simultaneously moving the ice-supporting means and the supporting means for the saws so as to carry the ice toward and from the saws, and means for rotating the saws continuously during their movement.

15. In a machine for scoring ice, the combination with a series of saws, means for supporting the same for bodily movement, means for rotating the saws continuously during their movement, means for supporting a block of ice, and means for connecting the ice-supporting means and the supporting means for the saws so that the weight of one serves as a counter-balance to the weight of the other.

16. In a machine for scoring ice, the combination of a saw carriage having vertically disposed saws mounted therein, a cage adapted to receive a block of ice, and means for moving the carriage downwardly and at the same time lifting the cage with a

block of ice thereon, the ice cage and saw carriage being so connected that the weight of the cage with the block of ice thereon is sufficient to overbalance the weight of the saw carriage and return the latter to its normal position.

17. In a machine for scoring ice, the combination of a saw carriage, and vertically disposed saws mounted therein, a cage adapted to receive a block of ice, means for moving the carriage downwardly and at the same time lifting the cage with a block of ice therein, means for returning the saw carriage while the ice cage moves downwardly, means engageable with a block of ice to discharge it from the cage after the latter descends, and means for scoring the ice longitudinally during its passage from the cage.

In testimony, that I claim the foregoing as my own, I have hereto affixed my signature.

R. H. ROARK.
